HEATING APPARATUS

Clyde Logsdon, Carthage, Mo.

Application July 12, 1945, Serial No. 604,631

3 Claims. (Cl. 237—67)

1

The invention relates to heating apparatus, and has for its principal object the provision of improved means for the conservation and utilization of heat in products of combustion which usually has been permitted to go to waste. While for purposes of disclosure the accompanying drawings illustrate examples of the application of the principles of the invention to a domestic heating plant, and to the utilization of waste heat in the exhaust gases of an internal combustion engine for the heating of the interior of an automobile, it will be readily appreciated by those skilled in the art that the invention is by no means limited to such uses, but that with relatively little change in the details of construction and arrangements of parts the apparatus may be readily employed, for example, for heating the cabin and/or de-icing the wings of an airplane, etc.

In the said drawings:

Figure 1 is a vertical sectional view, partly in elevation, illustrating a typical form of the invention applied to the chimney flue of a domestic heating plant;

Fig. 2 is a fragmentary sectional view on the plane indicated by the line 2—2 of Fig. 1, looking in the direction of the arrows;

Fig. 3 is an elevational view, partly in section, showing a modified form of the invention, adapted for the heating of an automobile;

Fig. 4 is an enlarged sectional-elevational view, showing the principal parts of this form more in detail; and

Fig. 5 is a cross sectional view on the plane indicated by the line 5—5 of Fig. 4, looking down.

Referring more particularly to Figs. 1 and 2 of the drawings, 5 indicates a chimney of brick or masonry work, provided with a metallic or other lining 6, and adapted to receive the smoke and gaseous products of combustion from a stove, furnace or other primary heating apparatus (not shown) through a smoke pipe 7.

Disposed within the pipe 7 is a plurality of strands 8 of a good heat conducting material, such for example as copper wires, and these strands extend into the flue 5 where they are wrapped around a vertical pipe or conduit 9, likewise of a good heat conducting material. Heat conducting strands 10, similar to the strands 8, are disposed within the pipe 9, which communicates at its upper end with a slightly inclined transverse chamber 11 extending across the flue 5. This chamber also contains heat conducting strands 12, and is entered at one end by a pipe 13 likewise containing heat conducting strands 14. The pipe 13 extends downwardly, either out-

2

side or inside the chimney 5, and its lower end is connected to heat exchanging box or chamber 15 which may be set in the floor 16 of the room or other enclosure to be heated.

A pipe 17 extends from the other end of the chamber 11, through the wall of the chimney 5, and is provided with a suitable check valve 18 for controlling the admission of air into the said chamber.

10 The lower end of the pipe or conduit 9 is provided with a horizontal extension 19 containing a suitable check valve 20, and this extension runs through a wall of the flue and communicates with the housing 21 of a float valve 22. Water is supplied to the valve housing 21 by a pipe 23 leading from any appropriate supply, such for example as a reservoir 24.

A drain pipe 26 leads from the box or chamber 15 and is provided with a suitable check valve 27.

20 The flue may be provided with a damper, comprising a pair of hinged leaves 28 which straddle the chamber 11, as will be clear from Fig. 2, and are adapted to be lowered from the full line to the dotted line positions shown, and vice versa, 25 by a chain 29 passing through a conduit 30 extending through a wall of the flue.

At the start of operation of the apparatus, the interstices between the strands 10, 12 and 14 are of course filled with air. The float valve 22 maintains sufficient water in the valve housing to keep the pipe 19 filled, and the check valve 20 permits a determined quantity to enter the lower part of pipe 9. As the combustion products pass through the smoke pipe 7 to the flue 5, the strands 8 become heated thereby and transfer such heat to the pipe 9 and the strands 10 therein. This pipe, as well as the chamber 11 and the strands 12 therein, may also absorb some heat directly from the combustion products; and since the strands 14 in pipe 13 are in contact with or constitute continuations of the strands 12, they too will become heated by conduction. The heated pipe 9 and strands 10 heat the air and water in the pipe, expanding the former and vaporizing the latter, thus setting up a pressure in the pipe 9, chamber 11 and pipe 13 which closes the check valves 18 and 20. These valves will thus prevent escape of the heated air and vapor through the pipes 17 and 19 and a flow will be set up down the pipe 13 to the heat exchanger box or radiator 15, where the heat from both the strands 14 and the air and vapor will be transferred to the air in the room or other space to be heated. From the box 15, the air and vapor (and any condensate from the latter) will escape through drain 26 and check valve 27. As such escape is completed, the

valve 27 closes and a slight negative pressure is established in the system, whereby the check valves 18 and 20 will again open, permitting a fresh charge of air and water to be introduced, whereupon the operation as above described will be repeated.

As above stated, the strands 14 tend to transfer heat from the chamber 11 to the box or radiator 15 by conduction. If these conductors were surrounded by air or water at the normal atmospheric temperature of the room or space to be heated, such fluid would absorb heat from the strands 14 and due to the convective currents set up in the fluid, transfer of the heat downwardly to the box 15 would be materially retarded if not entirely prevented. However, by the present arrangement, since the conductors 14 are surrounded throughout their length by the heated air and vapor, which move downwardly through the pipe 13 by reason of the pressure developed in the system, undue extraction of heat from the lower portions of the conductors is prevented, and as a result such lower portions may become substantially as hot as the upper portions and/or the strands 12 in chamber 11. The downwardly moving heated fluids of course also transfer heat to the box or radiator 15.

In the form of the invention shown in Figs. 3-5, the same essential elements are present, although structurally modified in some cases to adapt them to this particular use. The motor 35 of the vehicle is provided with the usual exhaust manifold 1' and exhaust pipe 5' which respectively correspond in function to the smoke pipe 7 and the flue 5 of the preceding form. The interior of the manifold is provided with strands or strips 3' of good heat conducting material, which have one of their ends secured by good heat transferring connections to a member 11', which may be conveniently introduced into the exhaust line at the flanged coupling usually provided between the manifold 1' and exhaust pipe 5', as will be readily understood from Figs. 3 and 4.

The block member 11' is provided with one or more passages or chambers 11a in which strands 12' of good heat conducting material are disposed, in contact with or constituting continuations of similar conductors 14' which pass through a pipe 13' to a box or radiator chamber 15', which may be contained within a housing 15a mounted on the dash of the vehicle. The passages 11a of the member 11' are connected by a pipe 9', controlled by a check valve 20', to the housing 21', of a float controlled valve, to which housing water is supplied from the cooling system of the motor by a pipe 23'. Air is supplied to the heating system by a pipe 17' controlled by a check valve 18', and a drain pipe 26' controlled by a check valve 27' provides for discharge of the condensate, in this instance back to the float valve housing 21'. A fan 36 may be mounted in the heater casing 15a, as is customary in devices of this character.

The operation of this form of the invention is substantially the same as that of the preceding form, except of course that the source of heat is the exhaust gases from the motor 35 rather than the products of combustion from a domestic heating plant.

From the foregoing it will be clear that the functioning of the present apparatus is not dependent upon the source of heat, or upon the space or device to be heated and therefore, as above indicated, within the scope of the appended

claims it may find ready and obvious applications other than the two specifically described.

What is claimed is:

1. In apparatus for utilizing waste heat in products of combustion, the combination with a passage through which the combustion products move, of a chamber disposed in conjunction with such passage to be heated by the combustion products therein; a radiator; a conduit connecting said radiator and chamber; metallic strands of high heat conductivity disposed in and extending throughout said chamber, conduit and radiator; means including a check valve for admitting air to the chamber and conduit; means including a check valve connected to the chamber for intermittently supplying water thereto for conversion into low pressure vapor, whereby to set up a flow of heated fluids through the chamber, conduit and radiator in intimate contact with the metallic strands therein; and means including a check valve connected to the radiator for discharging the fluids therefrom and setting up a slight negative pressure in the system to introduce additional air and water thereinto.
2. In apparatus for utilizing waste heat in products of combustion, the combination with a passage through which the combustion products move, of a chamber disposed in heat exchanging relation to said passage whereby to be heated by said products; metallic strands of high heat conductivity disposed in the passage exteriorly of the chamber and in heat transferring contact with a portion thereof to assist in heating it; a radiator; a conduit connecting said radiator and chamber; metallic strands of high heat conductivity disposed in and extending throughout said chamber, conduit and radiator; means including a check valve for admitting air to the chamber and conduit; means including a check valve connected to the chamber for intermittently supplying water thereto for conversion into low pressure vapor, whereby to set up a flow of heated fluids through the chamber, conduit and radiator in intimate contact with the metallic strands therein; and means including a check valve connected to the radiator for discharging the fluids therefrom and setting up a slight negative pressure in the system whereby to introduce additional air and water thereinto.
3. In apparatus for utilizing waste heat in products of combustion, the combination with a passage through which the combustion products move, of a chamber disposed in heat exchanging relation to said passage for heating by the combustion products therein; a radiator; a conduit connecting said radiator and chamber; metallic strands of high heat conductivity disposed in and extending throughout said chamber, conduit and radiator; means including a check valve connected to the chamber for admitting air thereto; a water reservoir having connections with the chamber; a float valve in said connections for intermittently admitting water from the reservoir to the chamber for conversion into low pressure vapor, whereby to set up a flow of heated fluids through the chamber, conduit and radiator in intimate contact with the metallic strands therein; and means including a check valve connected to the radiator for discharging the fluids therefrom and setting up a slight negative pressure in the system whereby to introduce additional air and water thereinto.

CLYDE LOGSDON.
